UNITED STATES PATENT OFFICE.

SAMUEL SEMMEL, OF BRONX, NEW YORK.

ADJUSTABLE TIE.

Application filed March 5, 1926. Serial No. 92,515.

The invention relates to an article of apparel constituting an adjustable tie of the type which is designed to fit snugly about different size collars. In adjustable band 5 ties heretofore known it has been a usual practice to provide for an adjustment including buckles and the like, and which known structures were objectionable for several reasons. For instance, either the 10 possible range of adjustment was extremely limited, or the buckle parts were either liable to be seen from the front of the wearer when adjusted to its small size, or it was just as apt to come across the rear collar 15 button where it was adjusted to one of its longer lengths.

Accordingly, the primary object of the present invention is to provide a form of tie which may have a relatively extensive 20 range of longitudinal adjustment and at the same time dispose the fastener or fasteners out of sight and within the limited space between the rear collar button and the point 25 over the wearer's shoulder where the tie begins to come visible from the front.

Various other objects and advantages of the invention will be in part obvious from an inspection of the accompanying drawings and in part will be more fully set forth 30 in the following particular description of one form of device embodying my invention, and the invention also consists in certain new and novel features of construction and combination of parts hereinafter set forth 35 and claimed.

Another object of the invention is to provide in effect a double ply portion across the rear collar button to permit an engagement through the retaining loop from the 40 shirt and at the same time provide in front a relatively single ply effect to facilitate the formation of a small bow.

In the accompanying drawing,

Fig. 1 is a view in front elevation of a 45 tie constituting a preferred embodiment of the invention shown knotted in position on a collar;

Fig. 2 is a plan view of the tie shown in Fig. 1 folded to economize in space; and

Fig. 3 is a vertical, transverse, sectional view through the double ply back position and associated dual fasteners and taken on the line 3-3 of Fig. 2.

The tie is formed of two end portions 50 and 11 of substantially equal length disposed with their inner ends 12 and 13 in

overlapped relation and with their outer ends 14 and 15 enlarged and fashioned to be tied together to form the front bow 16 as shown in Fig. 1.

A pair of slip buckles 17 and 18 are secured to the ends of the overlapped portions 12 and 13. The slip buckles are of a conventional flat form provided with a pair of parallel slits. In each case the inner end of the tie portions is threaded through one of the slits in its associated buckle and is then bent back upon itself and secured as by sewing. Each end portion of the tie in spaced relation to its associated buckle is 70 threaded S shaped through the two slits in the buckle secured to the other end portion. This S shaped bend of each end overlaps the bent back portion of the other end and frictionally engages the same. The engagement of fabric on fabric as the parts are threaded through the flat buckle assists in holding the tie ends fixed in their adjusted relation.

From this construction, it will be understood that in mounting the tie in position about the collar care will be exercised in locating the buckles 17 and 18 to position the same on opposite sides of the rear collar button 19 and spaced substantially equidistant from the collar button in opposite direction therefrom considered circumferentially about the collar band of the shirt. In this way, it is possible to obtain a rather extensive adjustment and at the same time maintain the fasteners within the limited space between the collar button and the points they would be apt to show from the front of the wearer. It is a usual practise to slip the tie through a band or retaining loop 95 formed at the back of full dress shirts for the purpose of holding the tie from riding upwardly on the collar. In the case of the tie herein illustrated, it is possible to make it of rather soft material but the double ply effect at the back of the neck when taken into consideration that this double ply portion is snugly fitting the back of the collar acts to maintain a smooth fit of the rear portion of the tie against the collar with little 100 if any ruffling which might otherwise be caused by the tendency of the tie to ride upward against the resistance of the loop projecting from the shirt.

It frequently happens that one side of a tie stretches more than the other side with the result that it is difficult to bring the bow

in proper position. With the form of construction herein disclosed, it is possible to adjust so that the bow will be centered even though the buckles in rear may be unequally spaced slightly from the rear collar button.

Having thus described my invention, I claim:

An article of apparel constituting an adjustable tie comprising two end portions of substantially equal length with their inner ends in overlapped relation and with their outer ends fashioned to be tied together to form the front bow or knot, a pair of flat slip buckles at the end of each end portion, 15 each slip buckle provided with a pair of

parallel slits, the inner end of each end portion passed through one of the slits of its associated buckle, bent back on itself and sewed to secure thereto the buckle at the end of each end portion, each end portion in spaced relation to its associated buckle being threaded **S** shape through the two slits in the buckle secured to the other end portion and lapping the bent back portion sewed to said buckle.

Signed at New York in the county of New York and State of New York this 26th day of February, A. D. 1926.

SAMUEL SEMMEL.
